(57) **CLAIM**

I claim the ornamental design for a laser target, as shown and described.

DESCRIPTION

FIG. 1 is a perspective view of a laser target showing the new design;

FIG. 2 is a right side elevational view thereof, the left side elevational view being a mirror image of the right side elevational view;

FIG. 3 is a top plan view thereof;

FIG. 4 is a bottom plan view thereof;

FIG. 5 is a perspective view of another embodiment of the laser target;

FIG. 6 is a right side elevational view of the laser target of FIG. 5;

FIG. 7 is a left side elevational view of the laser target of FIG. 5;

FIG. 8 is a front elevational view of the laser target of FIG. 5;

FIG. 9 is a rear elevational view of the laser target of FIG. 5;

FIG. 10 is a top plan view of the laser target of FIG. 5;

FIG. 11 is a bottom plan view of the laser target of FIG. 5 with the hook member in a closed position; and,

FIG. 12 is a bottom plan view of the laser target of FIG. 5 with the hook member in an open position.

A laser target having a translucent annular top surface area surrounding the raised center bullseye of the laser target as illustrated in FIGS. 1-3 and 5-10. The translucent surface may be of any color. The broken lines showing the mounting holes in FIGS. 4, 10, and 11 form no part of the claimed design.
